(57) **CLAIM**

The ornamental design for a combined clip and collar for reversibly attaching shelves to pole, as shown and described.

DESCRIPTION

(62) Division of application No. 14/750,492, filed on Jun. 25, 2015, now abandoned.

FIG. 1 is a top front left perspective view of a clip for reversibly attaching shelves to pole showing my new design; FIG. 2 is a front elevational view thereof showing the clip in an open position;

(51) **LOC (12) Cl.** **08-05**

FIG. 3 is a front elevational view thereof showing the clip in a closed position;

(52) **U.S. Cl.**

FIG. 4 is a bottom front left perspective view of the clip and a top front left perspective view of a collar for reversibly attaching shelves to pole that is mounted to a shelf and that is engaged on the clip;

USPC **D8/354**

FIG. 5 is a top front left perspective view of the clip and a top front left perspective view of the collar that is mounted to the shelf and that is disengaged with the clip; and, FIG. 6 is a top front left perspective view of the clip and a top front left perspective view of the collar that is mounted to the shelf and that is engaged with the clip.

(58) **Field of Classification Search**

The broken lines in the drawings illustrates portions of the combined clip and collar for reversibly attaching shelves to pole which form no part of the claimed design.

USPC D8/354, 349, 355, 363, 373, 380, 382,
D8/383, 394, 396

CPC A47B 57/56; A47B 45/00; A47B 81/061

See application file for complete search history.
